UNITED STATES PATENT OFFICE

135,617

DESIGN FOR A TELEPHONE BOOTH

George R. Lum, New York, N. Y., assignor to Bell Telephone Laboratories, Incorporated, New York, N. Y., a corporation of New York

Application September 19, 1942, Serial No. 108,278

Term of patent 14 years

To all whom it may concern:

Be it known that I, George R. Lum, a citizen of the United States, residing at New York city, in the county of New York and State of New York, have invented a new, original, and ornamental Design for a Telephone Booth, of which the following is a specification, reference being had to the accompanying drawings, in which Fig. 1 shows a perspective view of the telephone

booth of my invention, and Fig. 2 is a top view with the roof of the booth removed showing the interior of the booth, also showing that the rear of the booth and the opposite side to that of the side shown in Fig. 1 are similar in appearance.

I claim:

The ornamental design for a telephone booth, as shown and described.

GEORGE R. LUM.
